UNITED STATES PATENT OFFICE.

HAROLD E. NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR A COMPOTE OR ANALOGOUS ARTICLE.

Application filed April 1, 1929. Serial No. 30,695. Term of patent 7 years.

To all whom it may concern:

Be it known that I, HAROLD E. NOCK, a citizen of the United States, residing at Newburyport, in the county of Essex and Commonwealth of Massachusetts, have invented a new, original, and ornamental Design for a Compote or Analogous Article, of which the following is a specification, reference being had to the accompanying drawing, forming a part thereof.

In the drawing, Figure 1 is a plan view and Fig. 2 is a view in elevation of a compote showing my new design.

The dominant feature of my design consists in concentric sections of cones of equal pitch and of increasing diameters forming the bowl, and a series of circular steps forming the base of the compote or analogous article.

I claim:

The ornamental design for a compote or analogous article, substantially as shown and described.

HAROLD E. NOCK.
